UNITED STATES PATENT OFFICE.

CHARLES SEYBOLD, OF CINCINNATI, OHIO.

PAPER-CUTTING MACHINE.

SPECIFICATION forming part of Letters Patent No. 432,088, dated July 15, 1890.

Application filed January 14, 1889. Serial No. 296,312. (No model.)

To all whom it may concern:

Be it known that I, CHARLES SEYBOLD, a citizen of the United States, and a resident of the city of Cincinnati, county of Hamilton, 5 and State of Ohio, have invented certain new and useful Improvements in Paper-Cutting Machines, of which the following is a specification.

The object of my invention is to provide a 10 paper-cutting machine in which both the clamp and knife shall be operated by power and independently of each other.

The various other features and advantages of my machine will become apparent from the 15 following specification and claims and from the accompanying drawings, forming part of this specification, in which—

Figure 1 is a front view of my improved cutting-machine. Fig. 2 is a top view of the 20 mechanism for operating the clamp and knife, the table and upper parts of the machine being removed and the sides of the machine being in section. Fig. 3 is a side view of my machine—that is, the side opposite the side 25 at which power is applied. Fig. 4 is an end view of the gage-carrier, the table being shown in section. Fig. 5 is a sectional view of the knife, knife-bed, and knife and clamp. Fig. 6 is a view of the mechanism for automatically 30 reversing the knife-bed carrying the knife. Fig. 7 is a view of the clutch, sliding collar, clutch-band hub, &c., and miter-wheel (the parts being partly in section) for operating the clamp downward. Fig. 8 is a plan view 35 of the miter-wheel, &c., shown in Fig. 7, parts thereof being, however, in section. Fig. 9 is a plan view of one of the miter-wheels, clutch, and clutch-lever. Fig. 10 is an end view of the wheel shown in Fig. 9, and Fig. 11 is a 40 top view of the miter-wheel shown in Figs. 9 and 10. Fig. 12 is a side view of the lower or clamp-operating shaft and accompanying parts, and the shifting mechanism for throwing the lower clutch in and out to operate the clamp of the machine. Fig. 13 is a 45 top view of the treadle mechanism, the connecting or upright rods being shown in cross-section. Fig. 14 is an end view of the mechanism shown in Fig. 12, the lower clutch and 50 shaft being shown in section; and Fig. 15 is a view in section of the point of connection

between the rod N and arm N², the section being taken at the line 15 of Fig. 14.

A A' represent the sides or side castings of the machine, which are preferably formed as 55 shown, and are connected by a center cross-piece A² and a top piece A³, and also by guide-rods A⁵ A⁵.

B represents the front table, and B' the back table. The side castings A A' are provided at 60 their upper portions with the elongated slots B³. Directly below these slots B³, beneath the plane of the table, are cut the slots B⁹.

C represents the knife-bed, to which the knife C' is hinged in any suitable manner. 65

D represents the clamp, which may be made of any preferred form.

The knife-bed C is hung and swings on the arms C³.

D' represents the shaft which operates the 70 knife and knife-bed, and D² the shaft which operates the clamp. The shaft D' is formed with a left-hand screw-thread, and the shaft D² with a right and left hand screw-thread. The shaft D' carries at one end a fly-wheel D³ 75 and the tight and loose pulleys D⁴ and D⁵. The fly-wheel D³, tight pulley D⁴, and miter-wheel E are all mounted on a sleeve E', (see Fig. 1,) so as to operate together. The shafts D' and D² are journaled in each side of the 80 machine, passing through the side A, and are then journaled and supported in arms E² E² on a journal-bracket E'. The shaft D' carries the two vertical miter-wheels E and E⁴ and the shaft D² the two vertical miter-wheels 85 E⁵ and E⁶.

F represents a short vertical shaft (see dotted lines in Fig. 1) carrying at each end a miter-wheel F', which mesh with the miter-wheels E, E⁴, E⁵, and E⁶, and thus power is 90 transmitted from the lower shaft D². This gearing runs loose unless the clutch mechanism is thrown in. The clutch mechanism for the upper or knife-operating shaft is thrown in and out through the medium of the shifter 95 F² by working the handle F³ in the proper direction. The clutch mechanism for the lower or clamp-operating shaft D² is thrown in and out by operating the foot-treadle G. A screw-threaded nut H travels forward and 100 backward on the screw-threaded portion of the shaft D'. This nut H has two side arms

H' . (See particularly Fig. 2.) These side arms H' are connected at each side to the sliding guide-rods H^2 , which guide-rods keep the nut H from twisting and also guide it.

- 5 On each side of this nut H on the side arms H' are pivotally connected the long arms H^3 . At their opposite ends these long arms H^3 are pivotally connected to the lower end of the connecting-link H^4 and to the upper ends of 10 the curved links H^5 . These points of connection are made in any suitable manner. The lower ends of these curved links H^5 are connected pivotally to the side A' of the machine at H^6 . The link H^4 at its upper end is connected to the knife-bed C in any convenient manner.

The knife-bed C and clamp D are preferably constructed of the form shown, but may be modified.

- 20 As stated before, D' represents the knife-operating shaft. When motion is transmitted to said shaft by throwing the clutch into the miter-wheel E by means of handle F^3 , which is worked to the right, the nut H is forced to travel forward on said shaft, as are also the arms H^3 , and they being connected to links H^4 and curved links H^5 , said links are forced outward and downward, thus bringing down the knife-bed carrying the knife C' on the 25 paper to be cut and cutting same.

The knife-bed and knife are reversed as follows: On one of the sliding guide-rods H^2 is connected the finger K . This finger K has an eye which encircles the shifting-rod K' .

- 30 On said shifting-rod is attached a lug K^2 , against which the coiled spring K^3 , which encircles said rod K' , rests. To the side A of the machine I attach pivotally at K^4 a pawl-arm K^5 , (see particularly Fig. 6,) which pawl-arm is of the peculiar shape shown in said figure. Through the upper end of said pawl-arm I pass the adjustment-screw K^6 , held in proper position by the lock-nut K^7 . The foot L of this pawl-arm K^5 works in and out of the recess L' . (See dotted lines in Fig. 1.) When the nut H moves forward and the knife is coming down, the sliding rods H^2 , which are connected to said nut H by arms H' , are also moving forward, carrying with them the finger K , and said finger, being securely connected on said sliding rod H^2 , consequently pushes against the spring K^3 and places a tension upon it. When the knife has made its proper cut and has descended far enough, 45 the knife-bed C strikes the head of the screw K^6 on the pawl-arm K^5 , and therefore throws the said pawl-arm K^5 out of the recess L' , into which said pawl-arm had fallen when the knife came down. Thus the tension on spring K^3 is relieved, pulling the shifting-rod K' inward, and consequently throwing the clutch into the miter-wheel E^4 , turning shaft D' in the opposite direction, forcing the nut H backward and forcing the knife-bed and knife 50 upward. This reversal of the knife is therefore accomplished automatically.

As stated before, the lower shaft D^2 oper-

ates the clamp D , which shaft is operated by the lower set of gearing, to which motion is transmitted by the shaft F . (See Fig. 1.) 70 This shaft D^2 is screw-threaded right and left, as shown. The screw-threaded nuts M work forward and backward on this screw-threaded shaft D^2 , and each is provided with the side arms M' . These side arms M' encircle and 75 travel on the rods A^5 , so as to guide the nuts M and keep them from twisting. To the top of these nuts M are loosely connected the links M^2 . (See Fig. 1.) At their opposite ends these links M^2 are loosely connected to 80 the lower corner of the bell-crank M^3 , which bell-crank are loosely connected to the center piece A^2 of the machine. At their outward corners these bell-crank M^3 have attached to them at M^4 (see dotted lines in Fig. 1) the 85 lower ends of the connecting-rods M^5 . These connecting-rods are loosely connected at their upper ends at M^6 to the clamp D .

I will now describe how the clamp is brought down. The clutch must be thrown into the 90 wheel E^6 by operating the treadle G . This turns the shaft indicated by the arrows on said miter-wheel E^6 . The shaft being thus operated, the nuts M are forced to travel inward or toward each other, and traveling inward they force the bell-crank downward and inward through the agency of the links M^2 , thus pulling the connecting-rods M^5 and consequently clamp D downward until it reaches and clamps the work. When the 100 clutch is thrown into the miter-wheel E^5 , the screw-shaft D^2 revolves in an opposite direction and the nuts M travel outward or from each other, and consequently, through the agency of bell-crank M^3 and links M^5 , force 105 the clamp D upward.

The movements of the clamp and the mechanism for operating it are regulated, preferably, by the following devices, viz: To one end of the treadle G is suitably connected 110 one end of an upright rod N , which arm works loosely through an eye in the end of arm N' , which is connected to the center piece A^2 of the machine. Toward its upper end this rod N has attached to it in any preferred manner 115 the peculiarly-shaped arm N^2 . Preferably the rod N passes through an eye in one end of said arm N^2 , and is held in place by a thumb-screw, key, or the like. At its rear end this arm N^2 is attached in a similar manner to a connecting-rod N^3 , (see dotted lines 120 in Figs. 1 and 3,) which rod is in turn pivotally connected to the long bars N^4 N^5 . The bar N^4 is pivotally connected at N^6 to the side A' of the machine, and the bar N^5 at N^7 to 125 the lug P on the shifting-rod P' . A coiled spring P^2 extends from the table B , to which it is attached, to an extension P^3 on the treadle G . The miter-wheels E , E^4 , E^5 , and E^6 are of the peculiar shape shown in Figs. 9, 10, and 130 11, and the clutch being also of the form shown in said figures. (Also shown in Figs. 7 and 8.) The miter-wheel E^6 is, however, somewhat differently constructed. In it I

provide a series of pins R. These pins R are placed in recesses R' in the hub of the miter-wheel and rest against a small spring R² in said recess. This spring R² is present, so that 5 should the finger S perchance in its inward movement strike one of the said pins said spring will keep said pin from moving back too far, and also prevent said finger S from being jarred or broken. This finger S is attached to the sliding clutch-collar S' in any convenient manner, and is provided with an offset S². (See Fig. 7.) This offset catches or falls into a notch Y in the clutch-band hub Y'. (See Fig. 7.)

15 Having now described the devices for regulating the movements of the clamp and mechanism for operating it, I shall now describe how said devices work. When it is desired to bring down the clamp D, the operator 20 places his foot on the treadle G, presses it downward, and shifts it to the right until the lug G⁸ rests under the forked arm G⁹. (See Fig. 2.) By this movement the rod N is pulled downward, and as the peculiar-shaped 25 arm N² is connected thereto at one end by a pin n or the like (see Figs. 14 and 15) working in an elongated slot n', (see Figs. 14 and 15,) which slot is longest in a line with the length of said arm N², it also travels downward, and, owing to the presence of said slot n' in the arm N², a slight lateral or oscillating movement is imparted to the arm N, so as to allow the treadle G to be worked to the right or left, and also to assist in bringing 30 down the arms N⁴ and N⁵, and the arm N³, whose lower end is connected to the back end of the arm N², is also pulled down. Consequently the arms N⁴ and N⁵, to which the upper end of arm N³ is connected, are pulled 35 down, and the arm N⁵, being connected to the shifter P', pushes said shifter outward, and consequently throws the clutch into the miter-wheel E⁶, thus operating the shaft D², forcing the nuts M to travel inward, and, 40 consequently, through the medium of the links M², bell-cranks M³, and links M⁵, bringing down the clamp D. When the clutch has thus been thrown into the miter-wheel 45 E⁶, the finger S, which is attached to the sliding clutch-band S', has also been forced inward, and its offset S² has fallen into the notch Y in the clutch-band hub Y', and is traveling around with the clutch and miter-wheel E⁶. When the clamp reaches the work 50 and clamps it, the pressure on the clamp-operating parts stops the shaft D². The miter-wheels, however, continue to revolve, and when one of the pins R strikes the finger S it 55 throws it up and out of the notch Y in the clutch-band hub Y', throwing the sliding clutch-collar to the center through the agency of the spring P², on which there is a tension, which has been produced by the treadle being forced downward when the clutch was thrown 60 in and said parts are held in this position, provided the lug G⁸ on the treadle G rests against one of the forked arms G⁹, as shown in Fig. 2,

because the spring P², which is at a tension still, cannot lift up the treadle to its normal position. As the work is now clamped, I may 70 at any time move the treadle back into its normal position, as shown in dotted lines in Fig. 2—that is, away from under the fork G⁹—thus allowing the spring P² to pull up the treadle, and consequently the rod N and arms 75 N² and N³, thus pulling long rod N⁵ upward and inward, moving the shifter P' inward, and throwing the clutch into the miter-wheel E⁶, revolving the shaft D², and forcing the nuts M to travel outward and away from each 80 other, and, through the agency of links M², bell-cranks M³, and links M⁵, forcing the clamp to ascend. If it is desired to stop the clamp D in its upward movement, the screw P⁸ is so set in the lug N⁷ (see Fig. 1) on the shifting- 85 rod P' that the lug P⁹ on the link M² (see Fig. 1) in its backward movement will strike said screw P⁸, and thus, through the medium of the shifting-rod P', throw the clutch-sliding collar out of the miter-wheel E⁶ and to the 90 center, thus stopping the clamp D. By this means time is saved, as I need not wait until the clamp D has ascended to its utmost before bringing it down again.

I shall now set forth some of the other advantages of my machine. I hinge the knife C' to the bed-plate C in any convenient manner, preferably by hinges S³. By this construction the knife may be turned up, as shown in dotted lines in Fig. 5, and honed. 100 The gage is shown at the left hand in Fig. 3, and partly in Fig. 4. Partly this gage is formed similar to the angle-gage T now in use, as is also the finger-gage T'. This gage is operated forward and backward on the 105 screw T², passing through the screw-threaded nut T⁴. Said screw T² is operated by turning the hand-wheel T⁸. The remaining parts of said gage, consisting of bifurcated portion W, being V-shaped on its upper surface, and 110 the V-shaped recesses in which it travels, pin W' and the spring W², and the adjustment of the finger-gage T' and connecting parts, form the subject-matter of a separate application for Letters Patent. This gage is brought 115 up to the work by operating the screw T² in the proper direction, traveling in the V-shaped groove in the table B' until the work is gaged. It is operated away from the work in the same manner. When the finger-gage T' is used, it 120 is brought down, as shown in dotted lines in Fig. 3, and passed through slots in the table B', as is now customary in paper-cutting machines.

Y⁴ represents a sliding-gage clamp-piece 125 (see Figs. 1 and 5) held in position by a spring Y⁵. (See Fig. 5.) It slides down and up in the clamp D and is a part of it. By using it time can be saved when one sheet is to be cut or only a few sheets, or when it is desired to 130 cut at a certain line quickly on said sheets, as it may be pulled down to said line on the sheet to be cut, thus gaging the descent of the clamp D to the proper position on the sheet.

- The clamp D may then be lowered, and when down on the sheet said clamp and gage clamp-piece Y⁴ will be in the same plane and in the same vertical position. The knife may then 5 be brought down to make the cut.
- The operation of the clamp and its connections and knife and its connections has been described heretofore, and it will be seen from these descriptions that the clamp and knife 10 work independently, which feature has not heretofore been accomplished in power paper-cutting machines. It will also be seen that the clamp can be regulated at the will of the operator and that the knife is reversed automatically after making the cut. The means 15 for accomplishing these results have been specifically described and shown; but they may be altered and changed and equivalent devices used in their place or places.
- The various features herein shown and described are preferably used together; but parts of them may be employed in paper-cutting machines of a form different from the one herein specifically set forth. 20
- What I claim as new and of my invention, and desire to secure by Letters Patent, is—
1. In a paper-cutting machine, shaft D', nut H, arms H³, connected to links which are connected to the knife-bed C, knife C', shaft 25 D², nuts M, links M², bell-cranks M³, links M⁵, clamp D, and connecting and operating mechanism, substantially as described.
  2. In a paper-cutting machine, shaft D', screw-threaded, as specified, nut H, arms H³, connected to the knife-bed C, links H⁵, knife C', pawl-arm K⁵, shifter K', and means for 30 operating said shifter, substantially as set forth.

3. In a paper-cutting machine, shaft D', nut H, knife C', and connection between said 40 knife and nut, consisting of arms H³, links H⁴ and H⁵, in combination with sliding guide- rods H², substantially as set forth.

4. In a paper-cutting machine, shaft D', nut H, knife C', and connections between said 45 knife and nut, consisting of arms H³, links H⁴ and H⁵, in combination with sliding guide- rods H², shifter K', lug K, spring K³, and operating mechanism, substantially as set forth.

5. In a paper-cutting machine, shaft D², 50 nuts M, links M², bell-cranks M³, links M⁵, clamp D, and operating mechanism, substantially as set forth.

6. In a paper-cutting machine, shaft D², clamp D, nuts M, connections between said 55 nuts and clamp, in combination with a miter-wheel, as E⁶, having pins R, and peculiarly-shaped clutch-band hub, and finger S, substantially as set forth.

7. In a paper-cutting machine, two screw-threaded shafts, screw-threaded nuts traveling thereon, suitable connections between said nuts and the knife and clamp of the machine, in combination with two sets of miter-wheels, substantially as shown, and suitable 65 shifting mechanism, substantially as specified.

8. In a paper-cutting machine, shaft D², nuts M, clamps D, connections between said nuts and clamp, and arms M' on said nuts sliding on guide-rods, as A⁵, substantially as set forth. 70
